UNITED STATES PATENT OFFICE.

MONTRAVILLE M. WOOD, OF CHICAGO, ILLINOIS, ASSIGNOR TO GENERAL ELECTRIC COMPANY, A CORPORATION OF NEW YORK.

RAIL-BOND.

No. 895,928.

Specification of Letters Patent.

Patented Aug. 11, 1908.

Application filed September 9, 1901. Serial No. 74,786.

To all whom it may concern:

Be it known that I, MONTRAVILLE M. Wood, a citizen of the United States, residing at Chicago, county of Cook, State of Illinois, have invented certain new and useful Improvements in Rail-Bonds, of which the following is a specification, reference being made to the accompanying drawings, wherein—

10 Figures 1, 2 and 3 show in cross section different forms of my invention, and Figs. 4, 5 and 6 show the same forms respectively after pressure has been applied.

My invention relates to means for securing 15 rail-bond terminals to the rails which are to be electrically connected, and consists in a bond having a terminal adapted to enter an opening in the rail and containing a pointed or tapered pin with the tapering portion 20 thereof opposite the interior walls of the opening, so that the material of the terminal may be compressed and at the same time expanded within the opening by the spreading effect of the tapered pin upon such material 25 as it is forced longitudinally along the pin.

Referring to Fig. 1, A is a rail shown in section; B is a bond; C is a bond terminal consisting of a cylindrical lug projecting from the bond B and adapted to enter an opening 30 in the rail A. D is a pointed or tapered pin of hard material, preferably cast permanently in the terminal C. I also prefer to have the point of the pin contained within the material of the terminal so as to readily 35 pierce the same when pressure is applied. The opening in the rail may, if desired, be provided with undercut recesses *a* and *b*, or otherwise formed with retaining grooves or projections. The terminal C having the 40 original form shown in Fig. 1, with the pin D in place, is to be inserted in the opening in rail A as shown in Fig. 1. Pressure is then applied to the inner end of the terminal and the material thereof will thereby be forced 45 back longitudinally along the pin D and thereby expanded and headed over as shown in Fig. 4, so as to come into intimate contact with the inner walls of the opening and be permanently fixed and retained therein.

50 In Fig. 2 the pin D is shown as having a slightly different form from that appearing in Fig. 1, while in Fig. 5 the same is shown after compression.

In Fig. 3 the pin D has still a different 55 form, being in this instance tapered at both

its upper and lower ends and completely inclosed within the material of the terminal. In Fig. 6 the terminal of Fig. 3 is shown after pressure has been applied. In this case the pin D will be cast in the terminal C in the 60 process of manufacture, so as to be completely embedded therein.

It may be observed that the term "pin" is not quite so appropriate for describing the device of Figs. 3 and 6 as it is for the device 65 of Figs. 1 and 4 or Figs. 2 and 5. I, however, retain the term in the comprehensive sense of an internal expanding core harder than the material of the terminal, with the understanding that the word includes such a 70 core broadly whether it is of the form appearing in Figs. 1 and 4, or 2 and 5, or 3 and 6, or even if it takes any other form which will enable it to serve the purpose above described.

The pin will be of steel or other hard substance, while the terminal will be of copper or other substance softer than the pin. Obviously the compression of the terminal will in each case force the material down around 80 the diverging sides of the pin and thereby force such material outward against the walls of the opening.

What I claim as new and desire to secure by Letters Patent is:

1. The combination with a rail-bond terminal of solid metal, of a pointed piercing pin having its pointed end embedded in said metal.

2. The combination with a rail having an 90 opening therein, of a bond-terminal provided with an internal tapering pin and engaging the walls of said opening, the material of said terminal being compressed longitudinally along the said pin and thereby spread outward into intimate contact with the material 95 of the rail.

3. The combination with a rail having an opening therein with retaining recesses on the interior wall of the opening, of a bond-terminal provided with a tapering pin and contained in said opening, the material of said terminal being compressed and expanded by the said pin into intimate contact with the interior walls of the said opening.

4. The combination with a rail or other body having an opening therein, of a rail-bond terminal, a pointed tapering pin cast therein with its diverging sides opposite that portion of the terminal which is adapted to 110

be contained in said opening, whereby the material of the bond may be pressed longitudinally along the said pin and thereby expanded into intimate contact with the interior walls of said opening.

5. The combination with a rail-bond terminal of a pin therein pointed at both ends.

6. A terminal for rail bonds and similar electrical conductors, comprising a metallic plug-like head, and a spreader of relatively harder metal embedded therein, said spreader being so shaped that in the act of upsetting or compressing the head, it will direct and force the softer metal of the head to expand

15 laterally outward.

7. A terminal for rail bonds and similar electrical conductors, comprising a metallic plug-like head, and a spreader of relatively harder metal embedded therein, and adapted 20 to direct and force the softer metal of the head laterally outward in the act of upsetting or compressing the head, said spreader being so shaped that the zone of greatest expansion of the metal will be at substantially the center of the connection.

8. A terminal for rail bonds and similar electrical conductors, comprising a metallic plug-like head, and a spreader of relatively harder metal embedded therein, said spreader 30 being so shaped that in the act of upsetting or compressing the head, it will direct and force the softer metal of the head to expand outwardly in lines converging from opposite

sides of a transverse plane about centrally of the connection.

9. A terminal for rail bonds and similar electrical connections, provided with means when upsetting compression is applied for radially expanding particularly and principally the portion of the head midway between the ends.

10. In a rail bond, the combination with the rail having a hole of greater diameter at a point between its ends than at the entrance, and a terminal secured in the hole by expanding the metal to fill the enlarged inner part of the hole.

11. A rail bond connected to its rail by a plug-like terminal having its greatest diameter at a point between its ends, said terminal 50 being secured in a hole in the rail having a greater diameter between its ends than at the entrance.

12. In a rail bond, the combination with the rail having a hole of greater diameter at a point between its ends than at its entrance, and an expanded terminal secured in the hole and having a spreader or expander embedded therein.

In witness whereof I have hereunto set my hand before two subscribing witnesses, this thirtieth day of August, 1901.

MONTRAVILLE M. WOOD.
